UNITED STATES PATENT OFFICE.

CARL F. PEARSON, OF CHICAGO, ILLINOIS, ASSIGNOR TO THE TRIUMPH MOTOR CAR COMPANY, A CORPORATION OF ILLINOIS.

EXPLOSION-ENGINE.

No. 879,837.

Specification of Letters Patent.

Patented Feb. 18, 1908.

Original application filed September 22, 1906, Serial No. 335,835. Divided and this application filed February 13, 1907.
Serial No. 357,160.

To all whom it may concern:

Be it known that I, CARL F. PEARSON, a citizen of the United States, residing at Chicago, in the county of Cook and State of Illinois, have invented certain new and useful Improvements in Explosion-Engines, of which the following is a specification.

The object of my invention is to provide an improved reducing valve particularly adapted for use in connection with the starting device for explosion engines described and claimed in my companion application Serial No. 335,835, filed on or about September 22, 1906, of which application this is a division.

The drawing represents my improved valve in cross section, together with part of the apparatus to which it is connected. The valve seat is formed at the lower part of a casing 1. This casing is screw-threaded at the lower end to afford means for attaching it to the engine structure. The casing is formed with an upwardly directed shoulder 2 and is screw-threaded at its upper end. Seated upon the shoulder 2 is an outer casing 3 between which and the upper part of the inner casing 1 is an annular chamber 4. A screw-threaded cap 5 is mounted upon the upper end of the casing 1, and the lower edge of the cap bears upon the outer casing 3. Suitable packing rings 6 upon the lower edge of the cap and upon the shoulder 2 afford a tight joint at the upper and lower edges of the outer casing 3. A hole is tapped in the outer casing for the insertion of a pipe 7 which leads to a storage reservoir.

The lower end of the casing 1 is inserted in an opening in the engine casing adjacent to the intake valve of one of the four cylinders of the engine, and the interior of said cylinder 40 communicates with the reservoir through the reducing valve. The bore 8 of the inner casing is provided at its lower end with a conical valve seat 9. Co-acting with this seat is a valve 10 the upper part of which is square in cross section as shown at 11. The inner casing is provided with radial perforations 12 opposite the square part of the valve, thus affording direct communication when the valve is unseated between the cylinder space 45 and the storage reservoir. The upper end of the valve is provided with a stem 13 surrounded by a spring 14 which bears at its upper end against the cap 5 and at its lower

end against the valve, thus holding it to its seat.

The object of the mechanism with which my improved valve is used, as fully explained in my parent application referred to, is to store some of the gases resulting from the explosions, such stored gases to be used for the purpose of turning the engine over in starting. When the pressure due to an explosion in the cylinder with which the valve communicates is greater than that due to the spring 14, the valve 10 will be raised from its seat and part of the products of combustion will pass into the storage reservoir. This action will continue during the subsequent explosions in the cylinder to which the valve is connected until the combined pressure of the gases continue in the reservoir and of the spring 14 are greater than the pressure caused by such explosions. When this point is reached the valve will remain closed and the engine will operate in the usual manner, 75 the products of combustion remaining in the cylinder until released by the opening of the escape valve. If at any time the pressure in the reservoir falls below the desired limit the action of the valve will be automatically resumed and the desired pressure will be restored.

While I have described my improved reducing valve in connection with the starting device described in my companion application referred to above, it will be obvious that it is adapted for use in connection with any mechanism where it is desired to accomplish a similar function.

I claim:

1. A reducing valve, comprising an inner casing provided with a shoulder on its exterior, an outer casing resting at one end on said shoulder, and a cap engaging the opposite end of the outer casing and also engaging the inner casing.

2. A reducing valve, comprising a cylindrical casing screw-threaded at each end, a shoulder on said casing, a screw-threaded cap on said casing, an outer casing engaging said shoulder and cap forming a chamber which communicates with the interior of said inner casing and a spring pressed valve in said inner casing.

3. A pressure reducing valve for explosion engines, comprising a tubular portion having

a valve seat formed therein and radial cavities extending through the shell thereof, a plunger portion formed of substantially square stock and having a valve cone formed upon one end and a spring seat upon the other end thereof, a spring bearing upon the spring seat and mounted within the tubular portion, a cap threaded upon the end of the

tubular portion and forming a seat for the spring, and a cylindrical shell portion in- 10 closing a portion of the tube and forming a tight chamber about such tube.
